DESIGN FOR A COMBINED LAMP AND RADIO RECEIVING SET

John J. Punke, Detroit, Mich., assignor to Daniel J. Crowley, Grosse Pointe, Mich.

Application October 30, 1939, Serial No. 87,949

Term of patent 14 years

To all whom it may concern:

Be it known that I, John J. Punke, a citizen of the United States of America, residing at Detroit, in the county of Wayne and State of Michigan, have invented a certain new, original, and ornamental Design for a Combined Lamp and Radio Receiving Set, of which the following is a specification, reference being had therein to the accompanying drawing, forming a part thereof, wherein:

Figure 1 is a front elevational view of a combined lamp and radio receiving set embodying my new design; and

Figure 2 is a plan view of the design shown in Figure 1 with the shade unit removed.

The side of the base portion of the set opposite the side shown in the drawing and the adjacent sides are substantially the same in appearance as the side shown in the drawing, with the exception that the opening exposing the graduated dial is omitted.

I claim:

The ornamental design for a combined lamp and radio receiving set, substantially as shown and described.

JOHN J. PUNKE.
